Sheppard & Batts

UNITED STATES PATENT OFFICE.

ERNEST RIEBE, OF NEW YORK, N. Y.

BOOK-SUPPORT.

1,232,089.

Specification of Letters Patent.

Patented July 3, 1917.

Application filed December 23, 1916. Serial No. 138,534.

To all whom it may concern:

Be it known that I, ERNEST RIEBE, a citizen of the United States, and a resident of the city, county, and State of New York, 5 have invented certain new and useful Improvements in Book-Supports, of which the following is a description.

My invention relates to a device particularly adapted and intended to be supported by and in front of the user, and to receive and support a book or similar object in proper position to be easily read or examined by the user. It may also be used as a writing table and for other purposes.

15 The object of my invention is to produce a device of this kind that will be strong, compact and light, and which can be easily adjusted and held in position in front of the user.

20 In the drawing accompanying and forming a part of this specification, I have illustrated the preferred embodiment of my invention.

Referring to the drawing

25 Figure 1 shows the complete device in use; Fig. 2 is a plan view; and

Fig. 3 is a sectional view taken on the line 3—3 of Fig. 2.

Referring in detail to the structure shown, 30 the device comprises a flat board or table 1 provided at its rear edge with a strip or stop 2 and is adapted to receive and support a book or similar object, as shown at 3 in Fig. 1.

35 In order that the table 1 may be readily adjusted to and supported by the body of the user, I provide arms 4 which extend rearwardly. These arms are located one near each end of the table and slide in grooves 5 formed in the transverse strips 6 secured to the lower side of the board. A spring member 8 is secured to each arm at 9, and the cross member 10 which extends between the arms is secured to these spring members and 40 operates to hold the arms in proper alignment. The pins 11 are secured to the spring members 8 and are adapted to enter a series of holes 12 formed in the table, and thereby to hold the arms in any desired point of 45 adjustment. The cross member 10 not only operates to secure the arms to each other, but provides an easy means whereby the user may withdraw the pins and adjust the arms 4 by sliding them in or out, as desired.

13 is a flexible band adjustable as to length 55 by the buckle 14 adapted to bear against the body of the user. 15 is an adjustable band having its ends secured to the table 1, and this band is adapted to pass behind the neck or shoulders of the user, as shown in Fig. 1, 60 so as to coöperate with the other band and to support the table, as shown. The band 15 may be adjusted as to length by the buckle 16. By adjusting the lengths of the bands 13 and 15 and the position of the arms 4, 65 the device can readily be adjusted to the body of the user so as to support a book or similar object in proper position to be read or examined, thereby relieving the hands and arms of the user from this duty. It 70 may also be adjusted so as to be used as a desk or table for writing and similar uses.

While I have described only one embodiment of my invention, I am aware that modifications thereof may be made by those 75 skilled in the art without departing from the scope of my claims.

What I claim is:

1. A device of the kind described, comprising a table, rearwardly extending arms 80 slidably secured to the table, a spring member secured to the inner end of each arm, a cross member secured to said spring members and adapted to hold said arms in alignment, a series of holes in said table, pins 85 secured to said spring members and adapted to enter said holes, and to hold the arms in any desired point of adjustment, means secured to the outer ends of said arms and adapted to bear against the body of the 90 operator, and means secured to the table for supporting the device from the body of the operator, all for the purpose described.

2. A device of the kind described, comprising a table, rearwardly extending arms 95 slidably secured to the lower surface of the table adjacent its ends, a spring member secured to the inner end of each arm, a cross member secured to said spring members and adapted to hold said arms in alignment, a 100 series of holes in said table, pins secured to said spring members and adapted to enter said holes and to hold the arms in any desired point of adjustment, a band secured to the outer ends of said arms, and a band secured to the table, all for the purpose described. 105

ERNEST RIEBE.
